UNITED STATES PATENT OFFICE.

MARCELLUS S. FIELD, OF BOSTON, MASSACHUSETTS, ASSIGNOR OF TWO-THIRDS TO JAMES T. A. LEWIS AND JOHN T. WARD, OF SAME PLACE.

MAIL AND PACKAGE RECEPTACLE.

SPECIFICATION forming part of Letters Patent No. 672,417, dated April 16, 1901.

Application filed February 6, 1901. Serial No. 46,261. (No model.)

To all whom it may concern:

Be it known that I, MARCELLUS S. FIELD, a citizen of the United States, and a resident of Boston, in the county of Suffolk and State 5 of Massachusetts, have invented an Improvement in Mail and Package Receptacles, of which the following description, in connection with the accompanying drawings, is a specification, like characters on the drawings 10 representing like parts.

In the sorting of mail in post-offices it is usual to employ suitable receptacles into which is deposited the mail for different destinations, and similar receptacles are also 15 commonly used to receive mail from mail-chutes, these receptacles being usually baskets or similar repositories which when not in use occupy a good deal of space. Moreover, it is sometimes difficult to ascertain at 20 a glance whether the basket or other receptacle has any mail therein owing to the opaque character of the sides of the receptacle.

It is the object of this invention to provide a receptacle which is adapted to post-office 25 work, either to receive the mail from the mail-chute or to be used in the sorting of mail, which receptacle is collapsible and has its body composed of a reticulated fabric, so that the contents of the receptacle may at all times 30 be visible. The receptacle is also detachably secured to the wall or any other suitable support, whereby it may be easily removed when it is desired to discharge the contents therefrom.

35 My invention consists of a suitable framework, from which is suspended the body of the receptacle, which is preferably made from a reticulated fabric, and suitable brackets by which the frame of the receptacle is detach- 40 ably sustained, as hereinafter described and claimed.

In the drawings, Figure 1 is a perspective view showing my receptacle fastened to any suitable support, the body of the receptacle 45 being shown partially in outline. Fig. 2 is an enlarged perspective view of one of the brackets, showing in dotted lines the position occupied by one corner of the frame; and Fig. 3 is a plan view, on a smaller scale, of a modified form of receptacle-frame.

The invention comprises a suitable frame,

to which a collapsible body is attached, and suitable brackets, to which the frame is detachably secured, the brackets, it will be understood, being secured to the table or wall 55 or to any other suitable support in such a position as to place the receptacle convenient and accessible. The frame is designated generally by A, and it may be of any suitable shape, Fig. 1 showing a substantially rectangular frame and Fig. 3 showing a semicircular frame, and said frame supports in a manner hereinafter described the body B of the receptacle, which is composed of some flexible material, preferably some suitable reticulated fabric, such as netting, which will expose the contents of the receptacle to view at 60 all times. The brackets by which the frame is detachably sustained are represented by C, said brackets being more particularly herein- 65 after described.

The frame A is preferably made from a single piece of wire, which is bent into any suitable shape, but so as to make at least one straight side, which will be placed against 75 the wall or other support, and at the angles or corners of said frame, at the ends of said straight side, the wire of the frame is formed into suitable coils, as will be presently described. My preferred form of frame is illustrated in Fig. 1, which is rectangular in shape, this being preferable because it makes the receptacle a universal one, as will be herein- 80 after pointed out. As shown in Fig. 1, the rectangular frame has coils at each corner 85 thereof, and preferably these coils will be triangular in shape, as illustrated, and will be made by bending the side pieces 4 at 5 to make a right angle and again bending the wire at 6 to form an acute angle, carrying the 90 straight portion 7 of the coil across the corner of the frame and to the top of the side pieces 4 and then bending the wire back upon itself, as at 8, to make the upper turn 9 of the said coil, the said upper turn following the lower 95 turn 10 in making the corner of the frame. As stated above, each corner of the frame has a coil made in the manner above described, and, as will be seen from Fig. 1, the lower turn 10 of the coil above described merges into and 100 forms a continuation of the side piece 4, while the upper turn 9 merges into and forms

a continuation at one end of the side piece 4', said side piece 4' at its opposite end being bent to form the lower turn 10' of the coil at the next adjacent corner. From this construction it will be seen that each side piece 5 of the frame merges at one of its ends into the upper turn of one coil and at its opposite end into the lower turn of the next adjacent coil.

- 10 The body of the receptacle B is preferably made from any suitable open-work or reticulated fabric, such as netting, the advantages of this material being that the receptacle when not in use can be folded to occupy a 15 minimum space, and also when in use the open-work fabric allows the contents of the receptacle to be always visible from the outside. The reticulated fabric is suspended from the frame by stringing the loops at the 20 upper end of the body upon the side pieces of the frame, and at the corners the said loops pass over the piece 7 of the coil, which extends across the corner of the frame. With this way of attaching the fabric to the frame 25 when it is desired to discharge the contents from the receptacle the frame may simply be turned bottom side up, when the entire contents, together with the body B of the receptacle, will fall through the open framework, 30 the said body being turned wrong side out by this movement and in its new position being ready for use again without the necessity of passing the body back through the frame to its original position. It will thus be seen 35 that my receptacle is not only collapsible, but also reversible.

By making the frame A in the manner above specified—*i. e.*, with each side piece connecting the upper turn of one coil with 40 the lower turn of the next adjacent coil—it will be seen that if the empty receptacle were dropped on the floor each side piece would contact with the floor only at one end, and therefore the loops of the fabric which pass 45 around the said side pieces are raised sufficiently off the floor so that they are prevented from wearing.

The receptacle is usually supported, as illustrated in Fig. 1, by means of two brackets C, 50 which are made as rights and lefts, and each bracket comprises the base-piece 13, which is screwed to the wall or other suitable support, the said base-piece having projecting laterally therefrom the shelf or ledge 14, on 55 which the bottoms of the coils at the corners of the frame are adapted to be supported, the said ledge having preferably a slight upward incline, so as to maintain the frame of the receptacle at a slight upward incline when it is 60 in place. A suitable lug 15, projecting from the face of the base-piece 13, has its lower face cut away, as at 17, the point 18 of the lug being a distance from the shelf 14 slightly less than the thickness of the coil at the corners of the frame. A fin or side wall 16, con-

necting the base-piece 13 and ledge or shelf 14, serves to strengthen the bracket and also to provide a stop for preventing any side motion of the receptacle when in place in the brackets.

In placing the frame in position the front end thereof is raised slightly from the position shown in Fig. 1, when the rear portion of the coils may be slipped under the nose 18 of the lug 15 until the coils strike the base-piece 13 of the bracket. The front end of the frame is then lowered until the bottom of the coil rests squarely upon the shelf or ledge 14, the rear portion of the upper turns of the coils engaging the incline or cut-away portion 17 of the lug, thus holding the frame in a practically horizontal position and preventing the same from being disengaged from the bracket. When it is desired to empty the receptacle, the front portion of the frame is 85 raised slightly until the rear portion of the coils can be withdrawn from between the lug 18 and the shelf, when the receptacle can be readily removed from the brackets.

By making the frame rectangular, as shown 90 in Fig. 1, it becomes a universal frame, for since the side pieces are all of the same length the frame may be placed with any one of its sides against the wall, and it is not necessary in placing the frame in position to turn it 95 around to bring a certain side thereof between the brackets. The manner of attaching the fabric of the body B to the frame—that is, by stringing the loops on the side pieces and the inner portion 7 of the coils—100 allows the frame to be used either side up, as described above.

Fig. 3 illustrates a slightly-modified form of frame, which may be used instead of the rectangular frame, if desired, this frame having the straight side 21, at the ends of which are the coils, made as described above, the said coils being connected by the curved side 22. This form of frame, while it is reversible, is not universal, for it must always be 110 used with the straight side 21 against the supporting-wall.

It will be obvious that other shapes of frames may be used, provided they have the straight side which has the coils at each end 115 thereof, this being one of the important features of my invention.

Although my device is designed, primarily, for post-office use, yet it will be obvious that it is not confined to such use, for it is capable of use as a waste-basket or as a receptacle to hold any desired articles.

From the above it will be seen that I have devised an extremely light and portable mail-receptacle which when not in use can be collapsed and made to occupy a minimum space and which is so constructed that the contents thereof are at all times visible.

Various changes may be made in the structure outlined above without departing from 130

the spirit of my invention as expressed in the appended claims.

Having described my invention, what I claim as new, and desire to secure by Letters Patent, is—

1. A mail or package receptacle comprising a frame having a substantially straight portion, said frame made of a single wire which is bent to form coils at each end of said straight portion, a body for the reception of mail, composed of a reticulated fabric suspended from said frame, combined with a pair of brackets for detachably supporting the frame, said brackets each having a ledge or shelf on which the lower turns of the coils rest, and a lug engaging the top turns of said coils.

2. A mail or package receptacle comprising a rectangular frame made of a single piece of wire bent to form coils at each corner of the frame, each side piece of the frame connecting the top turn of one coil to the bottom turn of the next adjacent coil, a body for the reception of mail, composed of a reticulated fabric suspended from said frame, and means for detachably securing the frame to a support with the frame in a substantially horizontal position.

3. A mail-receptacle comprising a rectangular frame made of a single wire, said wire being bent to form triangular coils at each corner, a body for the reception of mail, composed of a reticulated fabric suspended from said frame, combined with a pair of oppositely-disposed brackets for detachably supporting the frame in a substantially horizontal position, said brackets each having a ledge on which the lower turn of the coils at the

corners of the frame rest, and a lug engaging the top turn of said coils.

4. A mail-receptacle comprising a rectangular frame made of a single wire, said wire being bent to form triangular coils at each corner, a body for the reception of mail, composed of a reticulated fabric suspended from said frame, combined with a pair of oppositely-disposed brackets for detachably supporting the frame in a substantially horizontal position, said brackets each having a laterally-disposed ledge on which the lower turn of the coil is adapted to rest, a lug adapted to engage the top turn of said coils, and a side wall adapted to engage the side of the frame and prevent lateral movement thereof.

5. A receptacle comprising a rectangular frame made of a single wire, said wire being bent to form triangular coils at each corner, each side piece of the frame connecting the top turn of the coil at one end thereof to the bottom turn of the coil at the other end thereof, a collapsible body suspended from said frame, combined with a pair of oppositely-disposed brackets for detachably supporting the frame in a substantially horizontal position, said brackets each having a ledge on which the lower turn of the coils at each end of a side piece of the frame is adapted to rest, and a lug adapted to engage the top turn of said coils.

In testimony whereof I have signed my name to this specification in the presence of two subscribing witnesses.

MARCELLUS S. FIELD.
